W. H. BROWN.

OIL CUP.

APPLICATION FILED FEB. 5, 1917.

1,308,331.

Patented July 1, 1919.

UNITED STATES PATENT OFFICE.

WILLIAM H. BROWN, OF CLEVELAND, OHIO.

OIL-CUP.

1,308,331.

Specification of Letters Patent.

Patented July 1, 1919.

Application filed February 5, 1917. Serial No. 146,708.

To all whom it may concern:

Be it known that I, WILLIAM H. BROWN, a citizen of the United States, residing at Cleveland, in the county of Cuyahoga and State of Ohio, have invented certain new and useful Improvements in Oil-Cups, of which the following is a specification.

My invention relates to closures for oil holes and the openings in oil cups through which oil is injected into the cup, or, into the duct leading to the machine parts which are to be lubricated. The principal object of my invention is to provide an automatic closing cap or closure which can be readily opened with the stem of an oil can, and which has means upon it to guide the stem of the oil can to the oil hole and prevent the stem from slipping out from under the cap.

20 A further object of my invention is to provide an oiler, the closure of which may be opened for the injection of oil without requiring any more space above the oiler when it is thus opened than is required 25 when it is closed.

A further object of my invention is to provide an oiler, the closure of which has a limited opening, and which automatically closes as soon as it is released.

30 A further object of my invention is to provide a novel and improved oiler which can be readily and cheaply manufactured, and is composed of few and inexpensive parts.

35 Referring to the drawings, Figure 1 is a front elevation of an oiler embodying my improvements.

Fig. 2 is a section on line II—II of Fig. 1.

Fig. 3 is a plan view of the oiler shown 40 in Figs. 1 and 2.

Fig. 4 is a front elevation of an oiler similar to that shown in Figs. 1, 2 and 3, with the exception that the body of the oiler is square throughout a portion of its 45 length.

Fig. 5 is a side elevation of the oiler shown in Fig. 4.

Fig. 6 is a plan view of the oiler shown in Figs. 4 and 5.

50 Fig. 7 is a rear elevation of a modified form of the oiler shown in Figs. 1, 2 and 3.

Fig. 8 is a section on line VIII—VIII of Fig. 7.

Fig. 9 is a plan of the oiler shown in 55 Figs. 7 and 8.

Fig. 10 is a perspective view showing the

stem of an oil can being inserted under the vizor of the cap of one of my improved oilers.

Fig. 11 is a perspective view showing the 60 stem of the oil can inserted under the cap in the position for injecting oil into one of my improved oilers.

Referring to Figs. 1, 2 and 3 of the drawings, reference numeral, 1, is the body of 65 the oiler having a threaded shank portion, 1^a, adapted to be screwed into a suitably threaded hole in the apparatus to be lubricated. This shank may be left plain for driving into unthreaded holes, when desired, in a manner well known in the art. An oil hole, 2, extends through the body of the oiler. The top of the oiler is inclined, preferably about forty-five degrees to permit the opening of the cap without its occupying more vertical space than is required when the oiler is closed, and to facilitate the insertion of the stem of an oil can from the side.

3 is a metal cap or closure for the oiler. 80 It comprises the top or cover portion which is extended in front as shown at 3^a, and is bent down at the sides as shown at 3^b, to form a vizor for purposes which will be described. The cap, 3, is hinged to the body, 85 1, by means of the pin, 4, which extends through the side walls of the body of the oiler, and through the flanges, 3^b, and is provided with heads, 4^a, or other suitable means for retaining it in position.

90 For the purpose of closing the cap, 3, I provide a coil spring, 5, which surrounds the hinge pin, 4, and has one of its ends attached to the cap as shown at 6, while its other end is extended downwardly and has 95 formed upon it a semi-circular loop, 6^a, adapted to engage the front and rear walls of the central opening, 2, of the oiler. The loop, 6^a, serves also as a means by which the spring may be seized and properly positioned to admit the hinge pin, 4, when the oiler parts are being assembled. When the parts of the oiler are assembled, the spring, 5, is given an initial tension so that it always tends to close the cap. I prefer to 100 join the top of the rear wall of the oiler to the top surface of the body by a curved surface, 1^b, tangent to the straight portion of the top of the body and concentric with the hinge pin, 4, and to form the rear end, 110 3^c, of the cap also concentric with hinge pin, 4, so that the opening in the oiler will be

completely closed by the cap, 3. The end of the curved portion, 3^a, of the cap, 3, serves as a limit stop when the cap is opened, by coming into contact with the rear wall of 5 the body, 1.

It will be seen that cap extension, 3^a, and flanges, 3^b, together form a guide in the shape of a vizor which is adapted to receive and guide the end of the stem of the oil can 10 into the cup. This prevents the stem of the oil can from slipping out from under the cap, which would allow the cap to close, and oil to be spilled on the outside. The flanges, 3^b, depend from the sides only of the cap, 15 and there is no depending flange over the front edge of the cup. This gives the underside of the cap a smooth surface and permits the end of the stem of an oil can to be placed under the vizor without any 20 particular care or accuracy, yet with assurance that the stem will be guided so as to properly inject oil into the cup. None of the existing oil cups with which I am familiar provides a closure having this feature. 25 In some of them the cap projects over the sides and front of the cup, but the depending flanges are also formed both at the sides and front of the cup, or there are no depending flanges at all. I have found my 30 construction to be extremely desirable and practical in that it permits the injection of oil into the oiler by the use of one hand only. In other oilers with which I am familiar, it is necessary to employ one hand 35 to hold open the cap while the other manipulates the oil can. In other oilers, there is a small projection provided on the cap, under which the stem of the oil can may be placed for opening the cap, but as there 40 are no flanges at the sides of this projection, it is difficult or quite impossible to open the cap with the stem of the oil can. In such oilers it is customary to arrange the cap so that it will remain open after it has once 45 been opened until it is closed by the attendant, thus increasing the time and care necessary to operate the oiler and increasing the chances for dirt to enter through forgotten open caps. It will be seen that my 50 construction overcomes these undesirable features and effects a saving of time, preventing annoyance and inconvenience to the attendant, and possible damage to the apparatus which the oiler serves.

55 In Figs. 4, 5 and 6, I have shown an oiler in which the body, 7, has a round shank, 7^a, but a square top, 7^b, to facilitate screwing the threaded shank into the apparatus to which the oiler is to be attached.

60 In Figs. 7, 8 and 9, I have shown an oiler similar to that shown in Figs. 1, 2 and 3, with the exception that the spring for closing the cap is formed differently, and reacts upon the body of the oiler in a different manner. In Fig. 8 the spring, 8, is

shown formed as a double coil spring having its outer ends, 9, secured to the cap and having its central loop portion, 10, engaging the top, 11, of the rear wall of the body of the oiler. A suitable recess is formed in 70 the top of this rear wall for the reception of the spring loop, 10, under the cap. The spring loop, however, so fills this recess that the cap effectively seals the oiler against the admission of dirt and foreign material. 75 It will be understood that a single coil spring may be substituted for the double coil spring in this form of my improvement.

In Fig. 10, I have shown a conventional perspective of any one of the forms of my 80 invention, with the stem of an oil can being inserted under the vizor for the purpose of lifting the cap.

In Fig. 11 I show the stem of the oil can inserted under the cap, the cap open, and 85 the oil can in position to inject oil into the oiler. It will be seen that the side flanges of the cap act as guides to prevent the stem of the oil can from slipping out from under the cap, while the vizor which projects beyond the body of the oiler, gives the end of the stem of the oil can an opportunity to start to lift the cap. I prefer to incline the top of my oiler in the manner shown, so that the stem of an oil can may be inserted into the opening from one side without requiring more vertical space than is occupied by the oiler when it is closed. By forming the oiler in this way, it is adapted 90 to be used in positions where there are obstructions close above it, and in which oilers having top openings only, can not be employed to advantage. I do not, however, limit the opening of the cap of the oiler to a horizontal position. It is evident that the 95 cap may be opened sufficiently to receive oil from a position vertically above the cup. 100

In addition to serving as a means for opening the cap, the overhanging sides and ends of the cap also form ample protection 110 to the oiler against the admission of dirt and water.

It will be apparent to those skilled in the art that modifications of my invention may be made without departing from its scope. 115

I claim and desire to secure by Letters Patent:

1. In an oil cup, a body portion having an inclined top surface provided with an oil receiving aperture, a hinge pin extending through the body portion in the angle formed by said top surface and the high side of said body portion, and a closure for said aperture hinged upon said pin and resting upon said top surface, said top surface being cut away at its uppermost end so as to permit the cap to swing about said pin as a hinge. 120

2. In an oil cup, a body portion having an inclined top surface provided with an 125

oil receiving aperture, a hinge pin extending through the body portion in the angle formed by said top surface and the high side of said body portion, said top surface 5 being rounded at its uppermost end to be concentric with said hinge pin, and a closure for said aperture consisting of a cap resting upon said top surface, and hinged upon said pin, and having the upper portion of 10 its inner surface formed concentric with said rounded end of said top surface to completely close said aperture and to permit said cap to swing open about said pin as a hinge.

15 3. An oil cup having a straight tubular body adapted at its lower end to be secured to the apparatus which it is to serve and having an inclined top surface surrounding the oil receiving aperture, the metal of the

tubular body being bent inwardly at the 20 top of its high side to overhang a portion of the said oil receiving aperture, a hinge pin extending transversely through the body portion in the angle formed by said inclined top surface and the high side of 25 said body portion, and a closure for said aperture having a cover portion resting upon said top surface and having depending side flanges hinged upon said pin, said cover portion being bent along its rear edge 30 to conform to the bent in portion of said body.

In testimony whereof I affix my signature in the presence of two witnesses.

WILLIAM H. BROWN.
